UNITED STATES PATENT OFFICE

2,223,088

ELECTRICAL APPARATUS

Donald M. Berges, Alpine, N. J., assignor to Bendix Aviation Corporation, South Bend, Ind., a corporation of Delaware

Application August 2, 1939, Serial No. 288,053

10 Claims. (Cl. 123—179)

This invention relates to electrical apparatus, and particularly to the control of current flow and electro-magnetic action.

An object is to provide unitary means for producing both electrical and mechanical energy flow—as, for example, the closing of an electric circuit and the coupling of mechanically rotatable members such as an engine crank-shaft and an engine-engaging gear or clutch for imparting initial rotary movement to such crank-shaft.

It has heretofore been proposed to incorporate circuit controlling means with engine-engaging mechanical linkage, as a means of insuring flow of current to an ignition facilitating agency—such as the induction coil 92, of Allen Patent No. 2,141,331—in synchronism with the movement of the engine-engaging member (of an engine starter) to engine-engaging position. When there is employed an ignition facilitating agency such as that shown at 92 in the Allen patent above identified (and also shown in the accompanying drawing at 79) it is customary to provide a special terminal on the conventional high tension magneto—such as the terminal indicated at 17 in the drawings of Hicks Patent No. 1,862,116 granted June 7, 1932—which terminal (as pointed out in the Hicks patent specification) receives high frequency current from such an engine starting auxiliary as is shown herein at 79; and this starting current is distributed to the various engine cylinders in correct sequence by utilizing the auxiliary or "booster" contact carried by the conventional magneto distributor (see Nowosielski Patent No. 1,654,993) and connecting sequentially with the points on the distributor block as the magneto distributor rotor turns in synchronism with the associated driving engine that is being started. Where such a device is employed in aircraft, the operation of the current controlling parts of the device is a cause of possible interference with the reception and transmission of radio signals; and an object of the present invention is to provide unitary circuit operating and work performing linkage involving such construction and inter-relationship of parts as to assure perfect shielding of the auxiliary ignition circuit against radio interference.

Another object is to provide for electro-magnetic operation of a unitary circuit operating and work performing linkage of the character indicated. In this connection a feature of the invention is the use of a single set of terminals for dual duty: first, for securing the ends of the magnet winding, and secondly, for anchorage of the

contact fingers constituting the normally separated elements of the switch controlling the flow of current to the ignition facilitating agency or other electrical unit to be energized concurrently with operation of the mechanical linkage above referred to.

These and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claims for this purpose.

In the drawing—

Fig. 1 is a central sectional view of a device embodying the invention;

Fig. 2 is a sectional view of a portion of the assembly of Fig. 1, showing the relationship of parts at a different stage in the operation; and

Fig. 3 is a diagrammatic illustration of one application of the invention.

In the several views the reference numeral 10 indicates a cup-shaped shell or housing element closed at one end by a plate 11 extending transversely thereof and abutting the associated housing section 12 having bosses 13 thereon facilitating support of the unit upon the housing of another device with which it may be operatively associated, as for example, an engine starting mechanism of the character shown in Patent No. 2,141,331 granted to Joseph W. Allen, and referred to above. Such mechanism includes an engine engaging clutch element shiftable in one direction in response to energization of the winding 14 of the solenoid assembly contained within the shell 10; a clutch element of this character being indicated diagrammatically at 15 in Fig. 3. 40

The plate 11 is provided with a central opening, and a guide member 25 is mounted with its outer end suitably fixed in said opening as by means of the upset flange or lip indicated at 26. The member 25 extends inwardly from the plate 11 and constitutes a fixed magnetic pole piece centrally located within the solenoid. A connecting member in the form of a rod 27 of non-magnetic material is mounted to slide freely within pole piece 25, and is provided at one end with a movable core or plunger 30 of magnetic material and of slightly smaller diameter than the outside diameter of the fixed pole piece 25. The plunger is suitably secured to the connecting rod 27 as by means of a pin 48, and at its opposite 55

end is centrally bored and threaded to receive a screw 33 having a head 34 adapted to receive pivotally one end of a lever or bellcrank 35 having connection at its opposite end 36 with the device to be actuated such as, for example, the clutch shifting mechanism of the above identified Allen patent. Also as in said Allen patent a suitable spring or equivalent means (not shown) may be provided to maintain the plunger rod 27 in the position indicated in Fig. 1 until such time as current is caused to flow through the solenoid winding 14, whereupon the resulting magnetic field produces an inward movement of the pole piece 30 to close the gap between the cooperating pole pieces 30 and 25 and thus produces movement of the linkage of which the elements 35 and 15 are parts.

A spool 38 of suitable insulating material surrounds the non-magnetic guide-sleeve 42 and receives the solenoid winding 14 as well as the terminal posts 39 and 40 which, as shown, are molded in the head portion 37 of the spool 38. At its outer end the terminal post 39 receives a contact finger 61 whose curved end 62 is adapted to rest upon the cylindrical surface of a switch element 63 mounted upon and movable with the plunger rod 27 upon which it is adjustably secured by suitable means such as the split rings 65 and 66; and a similar contact finger 67 is mounted on the terminal post 40 and is also adapted to rest upon the switch element 63—but at a point thereon which lies in a plane that is axially spaced from the plane of contact of the finger 61, so that in the normal position of the parts as shown in Fig. 1 the finger 61 rests upon the non-conducting portion 71 of the switch element 63 while finger 67 rests upon the metallic and hence current conducting portion 72. When, however, the plunger rod 27 is shifted to its opposite extreme position as by the passage of current through the winding 13 and the resulting closure of the air gap between the fixed and movable pole pieces 25 and 30, respectively, the switch element 63 rides along between the fingers 61 and 67 until both said fingers make contact with axially separated but electrically united portions of the metallic sleeve 71 of the switch assembly (as shown in Fig. 2), thereby completing a circuit from the source 18 (Fig. 3) to the ignition facilitating agency 19 by way of the switch contacts 80 (said switch having first been closed to energize winding 14), conductor 81, the finger 61, the sleeve 71, and the finger 67.

To employ motor M (Fig. 3) as the accelerating means for flywheel F of the engine starter, the operator may utilize the same source of current as for the energization of solenoid winding 14, and the motor control switch contacts 86 may be bridged by remotely disposed control, to permit use of a short heavy cable from source 18 to said switch contacts 86, and the installation of said switch in proximity to the motor housing. To this end there is provided a second solenoid 82 energizable to close switch 86, the flow of current to said solenoid being by way of normally open contacts 83, in shunt with contacts 80, and bridgeable by the same manually operable contact maker 84 as are the said contacts 80, although the said contact maker 84 is normally disposed in an intermediate position of nonengagement with either set 80 or the set 83.

Due to the above described connection to the magneto distributor, the wire leading from the auxiliary agency 19 necessarily enters the housing of the main magneto, and in consequence

thereof it is a potential source of interference with the reception and transmission of radio signals by means of radio equipment in adjacent locations. As a means of minimizing such interference I provide features of the switch structure which in and of themselves constitute a practically perfect barrier to radio frequency oscillations, since the exposed conducting portion 72 of the switch element 63 is in contact with finger 67 and therefore serves to ground the induction coil side of the switch (by way of rod 27 and housing 13) during the entire period in which the switch remains in open circuit position. Thus the element 63 tends to eliminate any positive capacitance value across the said fingers 61 and 67, by providing a path to ground for any energy oscillations in the area intercepted thereby.

In Fig. 1 there is also shown a desirable form of readily detachable terminal connection for switch finger 61, involving a spring-pressed snap rivet 68 registering with a slot in the lower end of finger 67, and removable with insulating bushing 69 whenever retaining nut 70 for cable 73 is unthreaded from its mounting boss on housing section 12.

What I claim is:

1. In a device of the character indicated, the combination of a set of current conducting switch elements, means including an insulating element normally preventing current flow from one of said switch elements to the other, current conducting means integrated with said insulating element and serving to intercept energy waves emanating from said switch elements, and means for moving the intercepting means to a position of current conducting relationship with respect to both said switch elements.

2. In a device of the character indicated, the combination of a set of current conducting switch elements, and means including a third current conducting member interposed between said switch elements and serving in one position to facilitate current flow from one of said switch elements to the other, and in another position to intercept energy waves emanating from said switch elements, and thereby eliminate any positive capacitance value across the said fingers.

3. In a device of the character indicated, the combination of a solenoid winding, a spool of insulating material to receive said winding, said spool having a pair of metallic terminal posts embedded therein, a current conducting switch element mounted on each of said terminal posts, and means including a third current conducting member interposed between said switch elements and serving in one position to facilitate current flow from one of said switch elements to the other, and in another position to intercept energy waves emanating from said switch elements, and thereby eliminate any positive capacitance value across the said fingers.

4. In a device of the character indicated, the combination of a set of current conducting switch elements, means including a third current conducting member interposed between said switch elements and serving in one position to facilitate current flow from one of said switch elements to the other, and in another position to intercept energy waves emanating from said switch elements, and thereby eliminate any positive capacitance value across the said fingers, and electromagnetic means for moving said third current conducting member from one of said positions to the other.

5. In a device of the character indicated, the

- combination of a solenoid winding, a spool of insulating material to receive said winding, said spool having a pair of metallic terminal posts embedded therein, a current conducting switch element mounted on each of said terminal posts, means including an insulating element normally preventing current flow from one of said switch elements to the other, and current conducting means integrated with said insulating element and serving to intercept energy waves emanating from said switch elements, thereby eliminating any positive capacitance value across said switch elements.
6. In an electro-magnetic device for use with internal combustion engine starting mechanism or the like, the combination of a set of ignition facilitating switch elements, means including an insulating element normally preventing current flow from one of said switch elements to the other, and common means including an electro-magnet for simultaneously connecting the engine starting mechanism with the engine and removing said insulating element from current flow preventing position.
7. In a device for use with internal combustion engine starting mechanism or the like, the combination of a set of ignition facilitating switch elements, means including an insulating element normally preventing current flow from one of said switch elements to the other, and common means for simultaneously connecting the engine starting mechanism with the engine and removing said insulating element from current flow preventing position.
8. In a device for use with mechanically rotated torque transmitting mechanism or the like, the combination of a set of current conducting switch elements, means including an insulating element normally preventing current flow from one of said switch elements to the other, current conducting means integrated with said insulating element and serving to intercept energy waves emanating from said switch elements, and common means for simultaneously moving the torque transmitting mechanism to torque transmitting position and the intercepting means to a position of current conducting relationship with respect to both said switch elements.
9. In a device of the character indicated, the combination of a solenoid winding, a spool of insulating material to receive said winding, said spool having a pair of metallic terminal posts embedded therein, a current conducting switch element mounted on each of said terminal posts, means including an insulating element normally preventing current flow from one of said switch elements to the other, current conducting means integrated with said insulating element and serving to intercept energy waves emanating from said switch elements, thereby eliminating any positive capacitance value across said switch elements, and electro-magnetic means operative upon the passage of current through said solenoid winding to move said intercepting means to a position of current conducting relationship with respect to both said switch elements.
10. In a device of the character indicated, the combination of a solenoid winding, a spool of insulating material to receive said winding, said spool having a pair of metallic terminal posts embedded therein, a current conducting switch element mounted on each of said terminal posts, means including a third current conducting member interposed between said switch elements and serving in one position to facilitate current flow from one of said switch elements to the other, and in another position to intercept energy waves emanating from said switch elements, and thereby eliminate any positive capacitance value across the said fingers, and means including magnetic pole pieces operative upon the passage of current through said solenoid winding to cause movement of said third current conducting member to a position of current conducting relationship with respect to both said switch elements.

DONALD M. BERGES.
